UNITED STATES PATENT OFFICE

HAROLD G. BARRETT, OF WILMETTE, ILLINOIS, ASSIGNOR TO PYRATONE PRODUCTS CORPORATION, OF CHICAGO, ILLINOIS, A CORPORATION OF ILLINOIS

APPARATUS FOR TAPERING TUBULAR SHAFTS FOR GOLF CLUBS AND THE LIKE

Application filed April 1, 1929. Serial No. 351,599.

This invention relates to improvements in apparatus for tapering hollow or tubular shafts for golf clubs and the like, and one of the objects of the invention is to provide 5 an improved apparatus of this character by means of which tubular shafts of non-metallic, hard and flexible material and of uniform diameter throughout their lengths may be tapered by subjecting the tube both externally and internally to the action of a heating medium such as steam, pressure being exerted from the inside of the tube to force the tube to conform to the contour of a tapering mold within which it is located. 10 A further object is to provide improved means for cooling or shrinking the tapered tube thus formed, sufficiently, to permit the same to be readily drawn out of the mold, and improved means for holding or maintaining the tube from shrinking longitudinally while it is being held in the mold. 15 To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which 20

Figure 1 is a side elevation of an apparatus of this character constructed in accordance with the principles of this invention.

Figure 2 is a sectional view taken on line 2-2, Figure 1.

Figure 3 is an elevation of a tube before the same is placed in the mold.

Figure 4 is an elevation of a tube after the same has been tapered.

Referring more particularly to the drawing the numeral 10 designates generally a casing which is preferably tubular in diameter and constructed of any suitable material. The ends of the casing are closed by means of end members 11-12 and supported within the casing by means of the end members is a tapering mold 13 which is constructed of any suitable material capable of being heated from the outside as well as the inside thereof. The ends of the mold 13 are supported by

the end members 11 and 12 of the casing 10.

An inlet pipe 14 has communication with the interior of the casing 10 and exterior of the mold 13, and an outlet pipe 15 leads from such casing.

Disposed adjacent the end members 11 and 12 are respectively arranged separable members 16-17 which are guided against the ends of the casing 10 and the end members 11 and 12 by means of suitable guides 18-19, and the proximate faces of the respective members 16-17 are grooved so as to conform to and engage the adjacent extremities of the tube 20 when the latter is placed in the mold 13.

The members 16 and 17 are adapted to be simultaneously separated in any suitable manner preferably by means of bell crank levers 21-22 pivotally supported intermediate their ends respectively as at 23-24. The levers 21 are provided with bifurcated extremities 25 which engage lugs 26 on the respective members 16, the lugs moving in suitable slots 27 in the guide members.

Similar bifurcated portions 28 are provided on one end of the bell crank levers 22 and these bifurcated portions engage lugs 29 connected with the members 17 and which pass through suitable slots 30 in the guide member.

The other ends of the respective levers 21-22 are connected by means of links 31-32 with a member 33 pivotally supported as at 34 and to which member 33 is connected an operating handle 35 so that when the handle 35 is operated to rock the member 33 about its pivot the respective bell crank levers will separate the respective end members 16-17 so as to permit the tube, after it has been shaped, to be withdrawn from the mold and also to permit a tube to be inserted into the mold.

The links 31 and 32 may be arranged on either side of the casing 10.

When the tube is placed into the mold 13 it will be of a length to extend beyond the ends of the mold so that when the respective members 16 and 17 are brought together by the operation of the handle 35 the ends of the tube will be grasped thereby. The outer faces

of the members 16—17 are respectively recessed as at 36—37 for a purpose to be set forth.

A nozzle 38 is suitably supported preferably upon a member 39 pivoted as at 40 so as to swing back and forth with the member 39 when the latter is operated. A catch 41 is pivotally connected as at 42 with the member 39 and is provided with a handle 43 together with a shoulder 44, the latter being adapted to engage over a portion 45 of the support 46 for the casing 10, and connected with the nozzle 38 by means of a flexible connection 47 is a valve casing 48 having a valve therein operable by means of a handle 49.

An inlet pipe 50 for a cooling medium is connected with the valve casing 48 and an inlet pipe 51 for a heating medium is also connected with the valve casing 48 so that by operating the handle 49 either a cooling or heating fluid may be directed through the nozzle 38. The nozzle is adapted to be inserted into the end of the tube 20 and to be secured in such position when the catch 41 is in the position shown in Figure 1.

A similar nozzle 52 is mounted upon a swinging support 53, the latter being pivoted as at 54. A catch 55 is pivotally connected as at 56 with the support 53 and is provided with a shoulder 57 and a handle 58. The shoulder 57 is adapted to engage over a portion 59 of a support 60 for the casing 10. The nozzle 52 is adapted to be adjusted in the same manner as the nozzle 38 and the end thereof inserted into the other end of the tube 20, and connected with the nozzle 52 by means of a flexible connection 61 is a valve 62 for controlling the connection.

Thus it will be seen when the valve 62 is closed and the valve 48 opened so as to admit the heating medium, it will flow through the pipe 20 to soften the latter or render it pliable and the pressure exerted by the heating medium on the inside of the pipe 20 will expand and taper the same by causing it to conform to the contour of the mold 13. The ends of the tube which are clamped or held by the end members 16—17 will not be expanded, but shoulders will be formed at the extremities of the tube 20, as shown more clearly in Figure 4 and these shoulders together with the clamping members 16—17 will hold the tube from shrinking lengthwise.

The heating medium which is delivered into the casing 10 through the pipe 14 will heat the mold from the outside thereof, thereby keeping the latter hot so that when the tube is placed into the mold and the heating medium discharged into the tube, it will be softened from both the inside and outside.

When the heating medium is turned off and the valve 48 adjusted so as to permit a cooling medium from the pipe 50 to be delivered through the nozzle 38, the cooling me-

dium will flow through the tube 20 and this will cause the tube 20 to shrink just sufficiently to permit it to be drawn out of the mold without chilling the entire mold, causing the tube to be readily removed without sticking to the mold.

Obviously the valve 62 may be opened when desired to permit the heating medium or the cooling medium to flow out of the tube 20 when desired.

After the tube has been thus shaped the extremities thereof may be cut off to any length desired.

Throughout the specification and claims wherever the term "shaft" is employed, it is to be understood that the same is to be construed broadly to mean either a shaft or a tube or both.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. An apparatus for expanding and tapering hollow non-metallic shafts, embodying a closed casing, an open ended tapering mold within and spaced from the wall of the casing, means for supplying a heating medium to the casing outside of the mold, means for clamping the ends of a tube inserted into the tapering mold and for holding the tube against longitudinal shrinking, means for introducing a heating fluid into the shaft to soften and shape the shaft, means for introducing a cooling fluid into the shaft, means for selectively controlling the last two recited means, and means common to said clamping means for rendering them active and inactive.

2. An apparatus for expanding a hollow shaft of non-metallic material of a normally uniform diameter, embodying a closed casing, a mold therein supported by and opening through the ends of the casing and into which mold the shaft is inserted, said mold being of an external diameter considerably less than the internal diameter of the casing, means for supplying a heating medium to the casing about the mold, clamping members adjacent each end of the shaft for clamping the ends of the shaft to hold the shaft from longitudinal shrinking movement, means for expanding the shaft in said mold, means common to the said clamping members for controlling them, and means for causing the shaft to disengage the wall of the mold whereby the shaft may be drawn out of the mold.

3. An apparatus for expanding and tapering a hollow shaft of non-metallic material of a normally uniform diameter, embodying

a closed casing, a tapering mold therein supported by and opening through the ends of the casing and into which mold the shaft is inserted, said mold being of an external diameter considerably less than the internal diameter of the casing, means for supplying a heating medium to the casing about the mold, clamping members adjacent each end of the shaft for clamping the ends of the shaft to hold the shaft from longitudinal shrinking movement, means for expanding the shaft in said mold, means for causing the shaft to disengage the wall of the mold whereby the shaft may be drawn out of the mold, and means for simultaneously rendering the said clamping members at both ends of the mold inactive to release said shaft.

4. An apparatus for expanding and tapering a hollow shaft of non-metallic material of a normally uniform diameter, embodying a closed casing, a tapering mold therein supported by and opening through the end of the casing and into which mold the shaft is inserted, said mold being of an external diameter considerably less than the internal diameter of the casing, means for supplying a heating medium to the casing about the mold, clamping members adjacent each end of the shaft for clamping the ends of the shaft to hold the shaft from longitudinal shrinking movement, means for expanding the shaft in said mold, the outer faces of said clamping members being recessed and into which recesses the extremities of the tube are deflected, and means whereby a cooling medium may be circulated through said shaft to release the latter with respect to the mold.

In testimony whereof I have signed my name to this specification, on this 12th day of

40 March, A. D. 1929.

HAROLD G. BARRETT.
